UNITED STATES PATENT OFFICE.

EDWARD LAWRENCE FISSEL, OF DAVISVILLE, CALIFORNIA.

DESIGN FOR A SEED-PLANTER ATTACHMENT.

SPECIFICATION forming part of Design No. 33,976, dated January 22, 1901.

Application filed December 27, 1900. Serial No. 41,292. Term of patent 3½ years.

To all whom it may concern:

Be it known that I, EDWARD LAWRENCE FISSEL, a citizen of the United States, residing at Davisville, in the county of Yolo and State of California, have invented and produced a certain new and original Design for Seed-Planter Attachments; and I do declare the following to be a full, clear, and exact description of the invention, such as will enable others skilled in the art to which it appertains to make and use the same.

The invention relates to a new and original design for a seed-planter attachment; and it consists of a design of the shape and configuration shown in the accompanying drawings, in which—

The leading feature of the design consists of a horizontal strip 1, having at one end a 20 downwardly-extending prong 2 and at the other end a downwardly-extending prong 3, terminating in an inwardly-extending plate 4, the surface of which is raised oblique to the strip 1. 25

What I claim is—

The design for a seed-planter attachment as herein shown and described.

In testimony whereof I have hereunto set my hand in presence of two subscribing witnesses. 30

EDWARD LAWRENCE FISSEL.
